Primary Examiner — Robin Webster(74) *Attorney, Agent, or Firm* — Calfee, Halter & Griswold LLP(57) **CLAIM**

The ornamental design for a spray device, as shown and described.

DESCRIPTION

FIG. 1 is a plan view of a first embodiment of a spray device of the new design;

FIG. 2 is a plan view of a second embodiment of a spray device of the new design;

FIG. 3 is a plan view of a third embodiment of a spray device of the new design;

FIG. 4 is a plan view of a fourth embodiment of a spray device of the new design;

FIG. 5 is a plan view of a fifth embodiment of a spray device of the new design; and,

FIG. 6 is a plan view of a sixth embodiment of a spray device of the new design.

The portions of the Figures shown in broken lines are not part of the claimed design and are for illustration only.
